UNITED STATES PATENT OFFICE.

CHARLES A. HART, OF SEATTLE, WASHINGTON.

OIL-BURNER.

1,346,373.

Specification of Letters Patent. Patented July 13, 1920.

Application filed December 13, 1919. Serial No. 344,702.

To all whom it may concern:

Be it known that I, CHARLES A. HART, a citizen of the United States, residing at Seattle, in the county of King and State of Washington, have invented a certain new and useful Improvement in Oil-Burners, of which the following is a specification.

My invention relates to improvements in oil burners of the type that are adapted to 10 burn hydro-carbon oils as kerosene and the object of my invention is to provide an oil burner that is inexpensive and simple in its plan of construction and that is efficient and reliable in operation.

15 Another object is to provide an oil burner in which the fuel conduit may be made from an ordinary piece of pipe bent to the desired shape and be supported above a cast base by a new and novel form of supporting 20 means.

A further object is to provide an oil burner in which the fuel conduit or pipe is disposed and arranged in such manner that it will be heated by the flame of the burner 25 sufficiently to gasify the fuel but will not be subjected to heat that is intense enough to cause the pipe to deteriorate rapidly.

A still further object is to provide an oil 30 burner that is adapted to be placed in the fire-box and rest upon the grate of a stove and that has the fuel conduit pipe so arranged that both ends of such pipe project downwardly through the stove grate, one of such ends being connected with a fuel 35 inlet pipe and the other of such ends having a removable cap thereon and serving as a trap in which residue from the fuel may collect.

The invention consists in the novel 40 construction, adaptation and combination of parts of an oil burner as will be more clearly hereinafter described and claimed.

In the accompanying drawings I accomplish the above objects and wherein—

45 Figure 1 is a plan view of an oil burner constructed in accordance with my invention;

Fig. 2 is a view in vertical section on broken line 2, 2, of Fig. 1, a portion of a 50 grate on which the oil burner may rest being shown in elevation;

Fig. 3 is a view in cross-section on broken line 3, 3 of Fig. 2; and

Fig. 4 is an enlarged view in cross-section

of the burner pipe on broken line 4, 4 of 55 Fig. 2.

Referring to the drawings, throughout which like reference numerals indicate like parts, the numeral 5 designates a base that is substantially plane and flat except that it is 60 provided in its central portion with a hollow raised burner support 6 having four convergent walls that form a truncated pyramid that is open at its top end as at 7. Two oppositely disposed walls of the truncated portion 6 are notched or grooved as at 8 to afford a rest for the lower portion of a 65 burner pipe as more clearly hereinafter described.

The bottom side of the base 5 is plane and 70 flat except that it is preferably provided around its outer edges with a rib 11 that gives strength to such base and that rests upon a grate 12 when the burner is placed in the fire-box of a stove.

75 The base plate 5 is provided with a medially arranged slot 9 that extends inwardly from one end of the base plate to the edge of the truncated portion 6 and affords an opening through which the burner conduit 80 or pipe may pass.

The burner conduit is preferably formed of a single piece of pipe and comprises an upright portion 13, an upper horizontal portion 14, a curved end portion 15, a lower 85 horizontal portion 16 that rests within the notches 8 in the truncated portion 6, and a downwardly projecting dead end portion 17 that is provided with a removable cap 18.

The upright portion 13 extends from below 90 the grate 11 upwardly through the slot 9 and is secured to the base 5 by two nuts 20 and 21 that are screwed on to the upright portion 13 and may be tightened against the top and bottom sides respectively of the base 95

5. The end 17 is bent so that it will project downwardly through the slot 9 adjacent the base of the truncated portion 6 and serves as a trap to catch residue from the oil that will not gasify. The end 17 may be easily 100 cleaned out by removing the cap 18.

The end of the upright portion 13 of the burner pipe is connected with a fuel supply pipe 22 through which fuel oil may be introduced either by gravity or under pressure.

105 The upright portion 13 of the burner pipe is packed full of wires 23 of relatively small

diameter, as shown in Fig. 4, that are inserted from the open bottom end and that serve both as a screen and as a heat retaining medium, the fuel being obliged to pass upwardly through the small spaces formed between the wires.

The lower horizontal section 16 of the burner pipe is provided on its top side and at a point substantially on the central axis 10 of the truncated portion 6 with a relatively small perforation 24 from which fuel in liquid or gasified form may be emitted.

If desired a flame deflector in the form of a disk 25 may be suspended from the horizontal upper section 14 of the burner pipe for the purpose of spreading the flame produced by the gas that is emitted from the perforation 24, such deflector also serving to prevent a jet of gas from impinging directly 20 on the pipe 14.

In starting the burner it will be necessary to permit some liquid fuel to flow from the perforation 24 and to run over the burner base where such liquid fuel may be ignited 25 and thus serve to heat the burner pipe. As soon as the burner pipe becomes hot the fuel therein will be gasified and the gas will be emitted from the perforation 24 and will unite with air and burn in the usual manner 30 making a hot flame that is practically free from soot and smoke.

Air is emitted through the truncated portion 6 and is directed inwardly by the convergent walls thereof toward the central jet 35 of gas in a manner best adapted to secure efficient combustion and produce a hot flame.

In experimenting with burners I have found that where the pipe is coiled so that a considerable length of pipe is subjected to 40 the greatest heat of the burner such pipe will be heated to a white heat when the burner is in use and will deteriorate rapidly.

The burner disclosed herein is made from a relatively short length of pipe which simply passes through the area of the most intense heat and which is arranged and disposed so that no part thereof is heated to a white heat which will cause the pipe to deteriorate rapidly and yet the heat is sufficient 50 to gasify the fuel before it is emitted from the perforation 24.

After the burner has been lighted the gasified fuel in the burner pipe will hold the liquid oil so that it cannot feed too fast.

Obviously changes may be made in the form, dimensions and arrangement of parts of my invention without departing from the spirit thereof.

What I claim is:

60 1. An oil burner comprising a flat base having a slot extending from one end thereof inwardly and provided with a hollow por-

tion of truncated pyramidal shape that projects above the upper surface thereof said hollow truncated portion being open at its 65 top end and having two of its oppositely disposed walls notched from the top downwardly, and a burner pipe comprising a U-shaped coil arranged in a vertical plane with its lowermost side resting in said notches 70 and its two ends bent downwardly and projecting through the slot in said base, the lowermost side of said U-shaped coil having an upwardly directed gas outlet perforation located centrally of said hollow truncated portion. 75

2. An oil burner comprising a flat base having a slot extending from one end thereof inwardly and provided with a hollow portion of truncated pyramidal shape that projects above the upper surface thereof, said hollow truncated portion being open at its top end downwardly, a burner comprising a U-shaped coil arranged in a vertical plane with its lowermost side resting in said 80 notches and its two ends bent downwardly and projecting through the slot in said base, the lowermost side of the U-shaped coil having an upwardly directed gas outlet perforation located centrally of said hollow truncated portion, and a plurality of wires disposed within one end of said burner pipe. 90

3. An oil burner comprising a flat base, having a hollow portion of truncated pyramidal shape that projects above the upper 95 surface thereof, said hollow truncated portion being open at its top end and having two of its opposite walls notched in the longitudinal medial plane of said base, said base having a slot that extends from one end 100 thereof inwardly to the edge of said truncated portion, a burner pipe comprising a vertically arranged closed end that projects upwardly through the slot in said base and is then bent at right angles to form a lower 105 horizontal portion that rests within the notches in said truncated portion and is provided with an upwardly directed gas outlet perforation, said horizontal portion then being bent double on a gradual curve to form 110 an upper horizontal portion that is spaced above and arranged parallel with said lower horizontal portion, the outer end of said upper horizontal portion being bent downwardly and projected through said slot, jam nuts on said downwardly bent portion and arranged to be tightened against the opposite sides of said base to support said burner pipe, and a plurality of wires disposed with 115 in the downwardly bent portion. 120

In witness whereof I hereunto subscribe my name this 8th day of December, A. D. 1919.

CHARLES A. HART.
